[57] CLAIM

The ornamental design for a handling container for granular materials, as shown and described.

DESCRIPTION

FIG. 1 is a bottom plan view of a first embodiment handling container for granular materials of this invention with a portion of a device for dosing granular materials, such as propellants, explosives and gunpowder, on which the container is mounted, being shown in dashed lines.

FIG. 2 is a side elevational view of the handling container of FIG. 1;

FIG. 3 is another side elevational view of the handling container of FIG. 1 as seen from a different direction, all sides of the container having the same appearance; FIG. 4 is a top plan view of the handling container of FIG. 1;

FIG. 5 is a bottom plan view of a second embodiment handling container for granular materials with a portion of a device for dosing granular materials, such as propellants, explosives and gunpowder, on which the container is mounted, being shown in dashed lines;

FIG. 6 is a side elevational view of the handling container of FIG. 5;

FIG. 7 is another side elevational view of the handling container of FIG. 5 as seen from a different direction, all sides of the container having the same appearance; and, FIG. 8 is a top plan view of the handling container of FIG. 5.

The broken line showing of the articles for dosing granular materials shown in Figs 1-8 is for illustrative purposes only and forms no part of the claimed design.
